COMBINATION TRASH AND GARBAGE CABINET

Earl J. La Pan and Thomas F. Dazey, Miami, Fla.; said
Dazey assignor to said La Pan

Application July 18, 1955, Serial No. 37,003

Term of patent 14 years

(Cl. D58—17)

FIG. 1

FIG. 3

FIG. 2

FIG. 4

FIG. 6

Figures 6 and 7 are perspective views thereof, showing the cabinet in partially open positions.

We claim:

The ornamental design for a combination trash and garbage cabinet, substantially as shown.
